UNITED STATES PATENT OFFICE.

FREDERICK SCHMIDT, OF WEST BEND, WISCONSIN.

FIFTH-WHEEL.

No. 839,324.

Specification of Letters Patent.

Patented Dec. 25, 1906.

Application filed November 10, 1905. Serial No. 286,639.

To all whom it may concern:

Be it known that I, FREDERICK SCHMIDT, residing in West Bend, in the county of Washington and State of Wisconsin, have invented new and useful Improvements in Fifth-Wheels, of which the following is a description, reference being had to the accompanying drawings, which are a part of this specification.

10 My invention has relation to improvements in fifth-wheels.

The primary object of the invention is to provide an improved construction of fifth-wheel wherein the two members of the fifth-wheel take the strain and the necessity for employing the ordinary form of king-bolt, which has heretofore been subjected directly to the strain, is obviated.

With the above primary object and other incidental objects in view the invention consists of the devices and parts or their equivalents, as hereinafter set forth.

In the accompanying drawings, Figure 1 is an under view of my invention. Fig. 2 is a 25 central longitudinal section through the device when occupying its proper position, and Fig. 3 is a front end view.

Referring to the drawings, the numerals 4 4 indicate two arms, preferably in the form 30 of a casting and provided with depending bearings 5 5 for the axle (not shown) of the wheel. These arms gradually converge and merge into each other rearwardly and are formed into a rounded crotch 6 at the point 35 of merger. The front ends of the arms are connected by the lower circular member 7 of the fifth-wheel, the said member being preferably formed in the same casting or integral with the arms. The upper surface of this 40 circular member is shouldered at opposite edges, as indicated by the numerals 8 8, and said upper surface from shoulder to shoulder is of convex form.

Above the arms 4 are other arms 9, and 45 bridging these arms is a bolster 10, preferably in one casting or integral with the arms. The front ends of arms 9 are connected by the upper circular member 11 of the fifth-wheel, which is also preferably in one casting 50 or integral with the arms. This upper member of the fifth-wheel in concavo-convex in cross-section, and its concavity fits the convex surface of the lower member of the fifth-wheel, the lower edges of said upper member 55 resting upon the shoulders 8 8. The two

arms 9 also converge and merge into each other rearwardly, and from the point of merger extend two divergent arms 12 12, to which arms the forward ends of the reach-bars (not shown) are connected. The rearwardly-extending divergent arms are also preferably in one casting or integral with the arms 9.

Depending from the arms 9 at the point of merger thereof is a pin 13, which fits in the 65 rounded crotch 6 and is provided at its lower end with an enlargement or head 14, which bears against the under side of the merged ends of the arms 4, and thereby not only assists in holding the two parts together, but 70 also forms the center of oscillation of the fifth-wheel.

From the foregoing description it will be seen that I provide a most simple form of fifth-wheel wherein the necessity of employing the usual king-bolt, which has heretofore been subjected to considerable strain, is entirely obviated and the entire strain is transferred directly to the two members of the 75 fifth-wheel.

It will be further noticed that my construction is such that the two upper arms 9, the upper circle 11 of the fifth-wheel, the bridging-bolster 10, the pin 13, and the rearwardly-diverging arms 12 may all be made in 85 one casting and integral and that also the lower arms 4 and the lower member 7 of the fifth wheel may also be in one casting or integral. By this provision a considerable saving in cost of manufacture is effected. 90

In order to prevent the two members of the fifth-wheel from separating to any considerable extent, I prefer to provide one of the members (the lower member being shown as so provided in the drawings) with a central 95 hook-like projection 15, preferably integral with the member from which it projects and extending forwardly and then rearwardly and over the other fifth-wheel member for a desired distance.

100 What I claim as my invention is—
1. In a fifth-wheel, the combination of a circular fifth-wheel member provided with a rearwardly-extending projection, another fifth-wheel member movably fitted to the 105 first-named fifth-wheel member and having a rearwardly-extending projection superimposed upon the projection of the first-named fifth-wheel member, the projection of one of the fifth-wheel members provided centrally 110

at its rear end with a projecting pin engaging a rounded crotch at the rear end and center of the other rearwardly-extending projection, the said pin forming the center of oscillation 5 for the fifth-wheel.

2. In a fifth-wheel, the combination of a circular fifth-wheel member, provided with a rearwardly-extending projection, another fifth-wheel member movably fitted to the 10 first-named fifth-wheel member, and provided with a rearwardly-extending projection superimposed upon the rearwardly-extending projection of the first-named fifth-wheel member, and the upper of said rearwardly-extending projections provided at its 15 rear end and at its center with a downwardly-extending pin engaging a rounded crotch at the rear end and center of the other rearwardly-projecting extension, the lower end 20 of said pin provided with an enlargement or head bearing against the lower rearwardly-extending projection, the said pin forming the center of oscillation for the fifth-wheel and the headed lower end thereof maintain-

ing the rear ends of the rearwardly-extending projections against separation. 25

3. In a fifth-wheel, the combination with arms converging and merging rearwardly and connected at their forward ends by a circular fifth-wheel member, of superimposed 30 arms connected at their forward ends by another fifth-wheel member, said arms also converging and merging rearwardly, and the said fifth-wheel members movably fitted together so that one may move in the arc of a 35 circle upon the other, and one of the set of arms at the point of merger provided with a projecting pin engaging a rounded crotch at the point of merger of the other set of arms, the said pin forming the center of oscillation 40 for the fifth-wheel.

In testimony whereof I affix my signature in presence of two witnesses.

FREDERICK SCHMIDT.
